UNITED STATES PATENT OFFICE

EMERY T. ERICKSON, OF CHICAGO, ILLINOIS

METHOD FOR REDUCING DRY GELATIN TO SOLUTION

Application filed March 8, 1930. Serial No. 434,472.

The invention relates to gelatin and more particularly it relates to an improved method and means for changing or transforming gelatin in the dry form of granules or flakes, assumed to be gelatin in the "hydrogel" state to gelatin dissolved in water or gelatin in the solution form, assumed to be gelatin in the "hydrosol" state.

The solubility of gelatin in water is a characteristic property recognized by scientific and technical workers in certain industries. For example, in the manufacture of confections such as marshmallows, the making of a proper solution of gelatin is an essential process. Not only is gelatin used as an ingredient of certain types of candies but it is a prominent ingredient in many other products.

The ordinary manual procedure and temperature relationships now employed in industries for putting gelatin in the solution state is to "soak" the dry gelatin in at least four times its weight of water at a temperature of 50 degrees Fahrenheit to 60 degrees Fahrenheit. The required weight of dry gelatin is very slowly "poured" into a vessel containing the required weight of water, accompanied by vigorous stirring. This stirring is to insure a complete wetting of each gelatin particle throughout the mass without the formation of "clumps" of dry gelatin as later described.

Shortly after pouring the dry gelatin into the water a phenomena known as the "swell" occurs, during which time the mass appears to undergo a radical change in consistency. The gelatin "soaks up" the water so that the result is a stiffened jelly-like substance. In this condition it is impossible to effect a further mixing or complete the wetting of the gelatin particles by the water so it is obvious that a perfect mixture should be effected in the short time interval before the "swell". After the "swell" the vessel containing the jelly-like water and gelatin combination is allowed to stand at room temperature for a period of time varying from a few minutes to an hour. The vessel is then placed in a water or steam bath to bring the contents up to a temperature of not more

than 150 degrees Fahrenheit, meanwhile being frequently stirred. At this temperature the contents of the vessel has lost its jelly-like property and has become a liquid.

In the above described process of putting 55 gelatin into solution, the experienced operator varies the time, temperature and concentrations within certain limits to secure the desired results. With certain types of gelatin it appears unnecessary to provide for 60 the time period after the "swell" period. In such cases the dry gelatin is poured into a vessel containing water at a temperature of 100 degrees to 150 degrees Fahrenheit, and the contents of the vessel then brought up 65 to a temperature of about 150 degrees Fahrenheit by placing the vessel in a hot water or steam bath as before described.

The preparation of a solution of a mass of gelatin, either flake or granular, by the methods heretofore practiced requires skill and strict and painstaking attention throughout the process to avoid waste and to obtain a thorough and uniform wetting of the mass, to effect the subsequent solution. In many 75 cases a waste of material and a solution not entirely satisfactory result even when the process is under the supervision of a careful and attentive operator. One of the undesirable results of putting the gelatin into solution, as at present practiced, is due to the pouring of a quantity of the dry grains or flakes of the gelatin into the water. If any attempt is made to hasten this operation, a membranous elastic coating or film forms around 85 and about the mass of dry gelatin in immediate contact with the water. This coating acts as an occlusive, tending to keep the water from access to the particles of the interior of the mass. Constant vigorous stirring for a more or less prolonged period of time after the solution is heated is required to break up this occlusive coating and the fresh coatings which form on the exposed surfaces of the mass as it is gradually broken 90 up. This stirring creates an undesirable amount of foam.

Gelatin is a complex protein substance of unknown composition. It has no definite melting point and there exists few reliable 100

physical tests of its properties. The property of the solubility of gelatin in water varies with time and temperature. The effect of time and temperature on the solution of gelatin cannot be foretold by inspection or analysis as is the case with substances of more definite composition. This limited knowledge of gelatin makes it highly desirable that the human equation be eliminated as much as possible in reducing any batch of gelatin to a solution.

The invention contemplates an improved method and means for changing or transforming gelatin from its dry state to its solution state and has among its objects; the putting of gelatin into solution in a period of time much shorter than has been heretofore required; the minimizing of labor required to change the gelatin from its dry state into its solution state; insuring the complete wetting or moistening of the surface of the dry gelatin particles in such a fashion as to effect complete solution without the formation of objectionable "clumps" of dry material; a method of reducing any batch of gelatin to a solution form requiring the minimum attention from an operator and in a manner in which no high degree of skill is required for successful manipulation; to the providing an improved method of putting gelatin into solution which prevents the formation of an occlusive film about a mass of relatively dry gelatin; the method of reducing the dry gelatin particles to a solution with a minimum foaming of the solution; reducing the loss of jelly strength of gelatin due to overheating and prolonged heating.

Many other further and more particular objects and advantages of the method and construction herein described and shown will be obvious to those skilled in the art from the description, disclosure and specifications herein given.

With the foregoing in view, this invention provides a method for thoroughly covering the surface of each grain, flake or particle of the mass of the gelatin or other material to be wetted or dissolved with water and a relatively simple means for regulating the proportions of the water and the gelatin or material as well as for controlling or regulating the temperature of the resulting solution.

Referring now to the drawings;

Figure 1 is a perspective view of a device with which the method of the invention is practiced; and

Figure 2 is a view of a portion of the device shown in Figure 1, drawn to larger scale.

Referring now more particularly to the drawings, the numeral 9 designates a standard, the lower end of which terminates in a base 8 of sufficient size to make the device stable and to prevent it from overturning easily. The standard 9 and its supporting base 8 provide a suitable and portable struc-

ture upon which the other elements comprising the device and utilized in practicing the invention are mounted. A water container 10 is mounted near the top of the standard 9 by means of a ring or band 7, fixed at a height to provide the water head sufficient to operate the device. A pipe 12 discharges the water from the container 10 through an annular ring, designated as 13. The ring 13 and the lower end of the pipe 12 are preferably horizontal and the ring is provided with a plurality of apertures or orifices 14, having their axes inclined downwardly and inwardly. The water escapes through the apertures 14 in fine streams or jets to form a conical shaped spray.

These fine streams impinge upon each other at a point in the vertical axis through the ring 13. A valve 15 is provided to control the rate of flow of water from the container 10 into the ring 13 and thence through the apertures 14.

A conical shaped hopper 11 is also supported on the standard 9 by means of a band 6 similar to the band 7. The hopper 11 is used as a receptacle for dry gelatin. The vertical axis of the hopper 11 is in alignment with the vertical axis of the ring 13 and has at its apex an opening 16 which permits the dry gelatin contained in the hopper 11 to flow in a fine stream downwardly into contact with the converging streams or jets of water at their point of impingement, thereby subjecting each particle of the dry mass of gelatin to contact with the water from all sides and thoroughly wetting and saturating the surface of each particle of the mass. The pipe 12 has its vertical portion of a length to provide for an adequate head sufficient to cause the streams of water coming through the apertures 14 to meet at a common point. Sprays of shapes other than circular may be provided, the only requirement being that they impinge a plurality of jets of water at a common point in the vertical axis of the hopper 11. A receptacle 19 is positioned on the base 8 to receive the mixture of gelatin and water flowing respectively from the hopper 11 and the container 10.

Describing now the method as practiced in connection with the device, the container 10 is filled with a measured quantity of hot water which may be at any temperature up to boiling. The water when released by valve 15 immediately starts to flow down the pipe 12 into the ring 13 and through the apertures 14. As soon as the water jets undergo impingement the dry gelatin, accurately weighed, is poured into the hopper 11 and immediately starts to flow through the opening 16, this flow continuing until the hopper is empty.

It is essential that the device be so constructed that the time period required for the flow of the entire gelatin content of the

hopper 11 through the opening 16 be not longer than the time period required for the flow of water from container 10 through pipe 12 and through the ring device 13.

5 The gelatin as placed in the hopper 11 is obviously at room temperature and if the water is placed in the container 10 at, say, 165 degrees Fahrenheit, it will, during the process of spraying on the dry gelatin and 10 subsequently falling into the receptacle 19 be cooled to a lower temperature, the amount of cooling depending upon a number of factors. These factors include the mass of water flowing through the ring relative to the mass 15 of dry gelatin flowing from the hopper 11; the temperature of each mass; the temperature of the room in which the operation takes place; the distance which the water-gelatin solution falls into the receptacle 19. By very 20 simple trial experiments, the temperature at which the water must be placed in the container 10 to secure a water-gelatin solution of a desired or prescribed temperature is easily determined.

25 The water-gelatin solution as it is received in the receptacle is ready for immediate use and due to the fact that the water wets and dampens and therefore "swells" the gelatin in a characteristic fashion no stirring is necessary and therefore foaming of the solution 30 is reduced to a minimum.

The invention contemplates as coming within its purview any means whereby each particle of the mass of gelatin or the like is 35 thoroughly saturated or "wet" as it enters the vessel in which the solution is to stand or to be used. The drawings illustrate a device which is found satisfactory in the practice 40 of the method comprising my invention, but it is understood that modifications depending on the particular application may be made in the same without departing from the spirit of the invention and I do not wish to be understood as limiting myself to the 45 exact form, construction, arrangement and combination of parts as shown.

The device has been in actual operation and has proven very effective in preparing 50 solutions of different concentrations of gelatin at various temperatures and various size batches, up to commercial batches totaling more than five hundred pounds of solution.

The method is adapted for putting crystalloids as well as colloids into solution, regardless of whether the crystalloids are readily soluble in water such as sugar for example, or whether they are of the type which it is desirable to wet or dampen before placing in solution such for example as boric acid.

60 Having thus described the invention, what is claimed is:

1. The method of saturating a mass of finely divided particles of material, which consists in creating an inwardly converging spray of liquid, causing the liquid comprising

ing said spray to converge substantially at a point, and then passing each of said particles through said point in single file.

2. The method of mixing a mass of granular material with a liquid, which consists in creating an inwardly converging spray of said liquid, causing the liquid spray to converge substantially at a point, passing the particles comprising said mass through said point and collecting the resulting mixture. 70

3. The method of mixing a mass of granular material with a liquid, which consists in creating an inwardly converging spray of said liquid, causing the liquid spray to converge substantially at a point, passing the particles comprising said mass through said point one by one and collecting the resulting mixture. 80

4. The method of saturating a mass of finely divided particles of material, which consists in creating and maintaining an inwardly converging spray of liquid, causing the liquid comprising said spray to converge substantially at a point and causing each of the particles comprising said mass to pass through 90 the point one by one.

5. The method of saturating a mass of finely divided particles of material, which consists in creating and maintaining an inwardly converging spray of liquid, causing the liquid comprising said spray to meet substantially 95 at a point, suspending said mass of material above said point, and permitting the particles comprising said mass to drop by gravity, one by one through said point. 100

6. The method of saturating a mass of finely divided particles of material, which consists in creating and maintaining an inwardly converging spray of liquid, causing the liquid comprising said spray to meet substantially 105 at a point, suspending said mass of material above said point, and permitting the particles comprising said mass to flow by gravity through said point in a fine stream.

7. The method of putting a mass of finely 110 divided particles of material into solution, which consists in creating an inwardly converging spray of liquid, causing the liquid spray to converge substantially at a point, then causing each of the particles comprising 115 said mass to pass through the point one by one and collecting the resulting mixture.

8. The method of putting a mass of particles of dry gelatin into solution, which consists in creating an inwardly converging spray of liquid, causing the liquid spray to converge substantially at a point, passing the particles comprising said mass through said point, and collecting the resulting mixture. 120

9. The method of putting a mass of finely 125 divided particles of dry gelatin into solution, which consists in creating an inwardly converging spray of liquid, causing the liquid spray to converge substantially at a point, suspending said mass of gelatin over said 130.

point, permitting the particles comprising said mass to drop by gravity one by one through said point, and collecting the resulting mixture.

- 5 10. The method of putting a mass of finely divided particles of dry gelatin into solution, which consists in creating an inwardly converging spray of liquid, causing the liquid spray to converge substantially at a point,
10 suspending said mass of gelatin over said point, permitting the gelatin to flow in a fine stream through said point, and collecting the resulting mixture.

- 15 11. The method of putting a mass of particles of dry gelatin into solution, which consists in heating a volume of water, causing the water to take the form of an inwardly directed spray converging at a point, suspending said mass above said point, permitting the
20 particles of gelatin to flow one by one through said point and collecting the resulting mixture.

- 25 12. The method of putting a mass of granular particles of gelatin into solution, which consists in heating a volume of water to a temperature substantially higher than the atmosphere, causing the water to take the form of an inwardly directed spray converging substantially at a point, suspending said
30 mass above said point, permitting the particles of gelatin to flow in a fine stream through said point and collecting and permitting the resulting mixture to stand until the gelatin goes into solution.

- 35 13. The method of saturating a mass of finely divided particles of material, which consists in providing a plurality of oppositely positioned sprays of liquid, causing said sprays to converge and intersect in a predetermined zone and causing the particles comprising the mass to pass successively through said zone, and then collecting the resulting mixture.

- 45 14. The method of bringing a finely divided mass of particles of material to be dissolved into intimate contact with a solvent, which consists in forming the solvent into oppositely positioned sprays, then directing the sprays inwardly to a predetermined zone
50 of intersection, then successively passing the particles through said zone of intersecting sprays of solvent, and then collecting the resultant mixture.

In witness whereof, I hereunto subscribe
55 my name this 4th day of March, A. D. 1930.

EMERY T. ERICKSON.
